(57) **CLAIM**

The ornamental design for a tape cartridge for a tape printer, as shown and described.

DESCRIPTION

FIG. 1 is a front view of a tape cartridge for a tape printer; FIG. 2 is a top view thereof;

FIG. 3 is a right-side view thereof;

FIG. 4 is a left-side view thereof;

FIG. 5 is a rear view thereof;

FIG. 6 is a bottom view thereof;

FIG. 7 is perspective view thereof; and,

FIG. 8 is a cross-sectional view thereof taken along the line 8—8 of FIG. 3 with a roll of tape removed.

The broken line showing is for illustrative purposes only, and forms no part of the claimed design.
